UNITED STATES PATENT OFFICE.

ELABURTON A. GALE, OF BELMONT, MASSACHUSETTS, ASSIGNOR, BY MESNE ASSIGNMENTS, TO REMINGTON RAND INC., OF NEW YORK, N. Y., A CORPORATION OF DELAWARE.

REENFORCING DEVICE FOR SIDES OF PERFORATIONS.

Application filed October 28, 1924. Serial No. 746,332.

This invention relates to reenforcing or strengthening devices for the sides of perforations particularly useful in connection with spacer sheets used in filing cabinets which are provided with apertures or slots adjacent their lower margins for receiving the usual locking rods to hold the sheets against accidental removal, and an object of the invention is to provide a device of this character which may be securely attached to a sheet in a ready and convenient manner and which is simple to construct and inexpensive to manufacture.

Further objects will hereinafter appear and the invention is shown in one of its preferred forms in the accompanying drawings in which.

Fig. 1 is a cross section of a filing cabinet drawer showing a spacer sheet in elevation provided with a reenforcing device;

Fig. 2 is an enlarged fragmentary elevation of the lower margin of the spacer sheet shown in Fig. 1;

Fig. 3 is a view of the opposite side of the spacer sheet and

Fig. 4 is a plan view of the reinforcing device.

The illustrated embodiment of the invention comprises a drawer of a filing cabinet having end walls (not shown) side walls 1 and 2, an open top 4, and a bottom 3 which is formed with a slot 5 extending longitudinally thereof. Arranged inside the drawer is a suitable number of spacer sheets 6 of relatively stiff material such as cardboard, bristol board or other suitable material which separate groups of papers or records from each other to keep the papers in position thus to facilitate finding of a certain paper. To identify the various groups tabs 7 may be fastened in any suitable manner to the upper portion of the spacer sheets and arranged to project above the margin of the sheets. These tabs may have suitable indicia according to the subject matter of each particular group.

In order to hold the spacer sheets in position and prevent them from being accidentally pulled out of the drawer when papers adjacent thereto are removed, each spacer sheet is provided with a tab 8 integral with the lower margin thereof which is arranged to extend into the slot 5 in the bottom of the drawer. Formed in the tab or extension 8 is a perforation 9 elongate longitudinally of the sheet which is arranged to receive the

usual locking rod 10 extending the length of the drawer and detachably connected to the opposite ends thereof. It will thus be understood that the rod 10 must be removed before the spacer sheets 6 can be withdrawn from the drawer.

It frequently happens that when papers or other contents of the drawer are withdrawn the spacer sheets 6 are accidentally grasped and if a sudden pull is exerted thereon the perforations 9 are torn out so that thereafter the sheets can not be held in position and their usefulness for the purpose intended is greatly impaired. In order to obviate this objection a reenforcing device A may enclose the lower margin of the tab or extension 8 and surround the perforation 9 in such a manner that outward pull on the spacer sheet 6 will not operate to tear the rod 10 out of the sheet because the device not only protects the edges or margin of the card immediately surrounding and forming the perforation but also reinforces a considerable part of the sheet in the vicinity of the perforation.

Preferably the reenforcing device A is constructed from a flexible, thin plate 11 of brass or other suitable material cut out to provide substantially a U-shaped notch 12 and a substantially Y-shaped notch 13 is formed in the sheet metal piece in opposed relation to the notch 12. In applying the device to the spacer sheet 6, the metal piece is folded approximately along the line 14 over the lower margin of the tab or extension 8 in such a manner that the notch 12 partially surrounds the perforation 9, as indicated. To hold the device A securely in position flaps 15 which are formed by the Y-shaped notch are folded approximately along the dotted lines shown in Fig. 4 through the perforation 9 and over the opposite side of the device. The edge of the card which forms the perforation is thus firmly gripped between the two metal pieces, when the flaps 15 are passed through the perforation and folded down on the opposite side. Preferably three flaps 15 are provided on the reenforcing device arranged on three sides of the perforation 9 so that the portion of the card on each side of the perforation subjected to strain is adequately reinforced, thereby preventing tearing under all conditions of use.

Owing to the fact that the plate 11 encloses a considerable portion of the tab or extension 8 in the vicinity of the perforation 9 creasing

or folding which would weaken the connection between the sheet and locking rod 10 is prevented. A further advantage of the device resides in the fact that there are no sharp 5 projecting edges which would prevent a number of sheets from being arranged closely together.

Although I have shown and described a construction which at this time is the best 10 form known to me, it is to be understood that numerous changes in details of construction, arrangement and selection of materials may be effected without departing from the spirit of the invention especially as defined in 15 the appended claims.

I claim:

1. The combination with a sheet or card having a perforation adjacent a margin thereof, of a pair of elements on opposite sides of 20 the sheet in the region of said perforation, and integral parts on one element for engaging the other, passing through the perforation and reenforcing the sheet surrounding the perforation and adjacent the margin.
2. The combination with a sheet having 25 a perforation adjacent a margin thereof, of a member enclosing the adjacent margin of the sheet and having extensions on opposite sides of the sheet in the vicinity of the perforation, and an element integral with one of

said extensions engaging the other extension through the perforation and firmly gripping the sheet therebetween, thereby to protect the sheet from tearing in the direction of the margin.

35

3. The combination of a spacer sheet having a marginal extension at one end thereof, said marginal extension having a perforation to receive a rod for locking the spacer sheet in position, and means for reenforcing 40 said perforation comprising a sheet metal plate enclosing the margin of said extension and constructed partially to surround said perforation, and tabs on a portion of said plate arranged to extend through said perforation and fold over another portion of the plate to the sheet.

45

4. A device of the class described comprising a plate constructed to be folded over a 50 margin of a sheet having cut-out portions and designed to partially surround a perforation in said sheet when folded, and foldable tabs integral with a portion of the plate arranged to extend through the perforation 55 and engage another portion of the plate thereby to reinforce the sides of the perforation.

Signed by me at Cambridge, Massachusetts, this 24th day of October, 1924.

LABURTON A. GALE.
